CLAIM

The ornamental design for a broom head, as shown and described.

DESCRIPTION

FIG. 1 is a perspective view of the new design for a broom head;

FIG. 2 is a right side view thereof, the left side view being a mirror image thereof;

FIG. 3 is a front view thereof;

FIG. 4 is a rear view thereof;

FIG. 5 is a bottom view thereof;

FIG. 6 is a top view thereof; and,

FIG. 7 is a reduced perspective view thereof showing the broom head with a long handle.

The portions of the broom head shown in broken lines in the figures along with the environmental broken line showing of a handle in FIG. 7 form no part of the claimed design.

1 Claim, 5 Drawing Sheets(56)
